RADIOCABINET

John E. Grimm, Dayton, Ohio, assignor, by mesne assignments, to Radio Corporation of America, New York, N. Y., a corporation of Delaware

Application April 20, 1931, Serial No. 531,354

4 Claims. (Cl. 312—7)

This invention relates to radio cabinets, or those cabinets adaptable for the housing of radio receivers and like mechanisms.

One of the objects of the invention is to provide a suitable closure for an irregular shaped opening.

A further object of the invention is to provide a closure for an opening in an instrument cabinet, whereby said opening may be opened and closed without interrupting the outline contour of the said cabinet either in the open or closed position.

A further object of the invention is to improve radio cabinet structure in general.

Further objects and advantages of the present invention will be apparent from the following description, reference being had to the accompanying drawings wherein a preferred embodiment of one form of the present invention is clearly shown.

In the drawings:

Fig. 1 is a front elevational view of a radio cabinet exhibiting the instant invention, in which the closure member is in the open position.

Fig. 2 is a transverse sectional view of the same substantially as illustrated on the line and in the direction of the arrows 2—2 of Fig. 1.

Fig. 3 is a vertical sectional view of the same substantially as illustrated by the line and arrows 3—3 of Fig. 1.

Fig. 4 is a fragmentary view showing a detail of the construction by which the closure member is automatically latched into position.

Fig. 5 is a sectional view of the same, substantially as illustrated by the line and arrows 5—5 of Fig. 4.

Figs. 6, 7 and 8 are top plan views of modified forms of cabinets, in which the instant invention has been adapted.

With particular reference to the drawings, considering first Figs. 1 to 5 inclusive, the numeral 20 represents a radio cabinet of conventional structure, comprising in main a front wall 21, end walls 22 that may be joined by appropriate cabinet work and include the corner or post members 23, the lower portion of which is turned into the preferred design of leg or standard 24. The tops and bottoms of the various panels are additionally reinforced and joined to the post members by appropriate rails 25 for the side members, and the rails 26 and 27 with an attached apron 28 for the front wall 21, and such other necessary or desired elements of cabinet structure as may be preferred.

A top member 29 finishes off the top of the

instrument, while the interior thereof is substantially divided into a pair of compartments 30 and 31 by a partition like member formed from the supporting rails 32 and 33 joined by the cross rails 34 and 35, and having appropriate support from the post members 23 by morticing therein, and may include the stop or corner blocks 36, these said rails so supported from the cabinet structure forming a base upon which to mount or secure the radio chassis, or the receiving instrument. The compartment 31 below the so called partition is further divided, or at least supports a baffle board 40 having an aperture 41 that provides for the mounting of a suitable speaker, which board in the illustrated embodiment, is tilted as illustrated in Figs. 2 and 3.

The front wall 21 of the instrument, may be of any preferred contour or design substantially as suggested by the drawings, but for the purpose of illustration one having an offset or irregular face member has been selected, in which the main portion of the panel 21 is set out as at 45, which set out portion encloses a secondary panel 46, that is apertured at 47 with an irregular shaped opening as illustrated, so as to give access to the control elements and inspection aperture of the contained receiver that may be accessible from the front of a radio instrument panel 48. This instrument panel 48 is preferably secured to the forward portion of the cabinet, which in the present instance is accomplished by the rails or spacers 49 and 50 attached to or otherwise secured to the panel member 46. It is preferred that these rails 49 and 50 be of substantial thickness, so as to space the instrument panel 48 from the member 46 sufficiently to provide a chamber 51 between the panel 48 and a sliding door 55 that slides vertically in grooves 56 and 57 cut in the opposing faces of the rails 49 and 50 at their portions contiguous to the panel 46.

The instrument panel 48 may be apertured at 60 to provide inspection of a dial situated therewith, and also carry the apertures 61, 62 and 63 that are adaptable for appropriate controls of the receiving instrument, substantially as indicated in Figs. 2 and 3. It is thus seen that the spacing of the instrument panel 48, by the rails 49 and 50, from the closure member 55 provides a suitable chamber 51 for the housing of the various controls of the receiving instrument.

The closure member 55 may be either of flattened or curved structure, as is illustrated in the drawings, but in preference comprises a slidable panel of the desired form which may be reinforced with the moldings or beads 65 and 66 for

the purposes of rigidity or finish, but in all events is to be of over all dimension substantially less than the distance between the bottoms of the grooves 56 and 57, so that the sliding panel 55 will have a loose fit so to slide within the channels formed in the rails 49 and 50. This makes provision for suitable springs 67 that may be secured to the bead or molding 66 substantially as illustrated in the detail of Fig. 4. In the disclosure here presented, the spring 67 is in the form of a long bow spring fixed at its middle region to the rail 66 by the screws or similar devices 68, and has its oppositely extending free ends 69 and 70 firmly engaging the rail 49 and recurved so as to provide a smooth movement over the surface of the rail. When assembled, that is when the sliding panel 55 is disposed within its companion guideways formed by the grooves 56 and 57, the spring 67 is under considerable stress due to its compression or flattening out from its free state, and this makes for smooth and easy movement of the closure 55 throughout the length of the guideways 56 and 57, since the member engages the rail 49 with the same amount of frictional force throughout its entire range.

In one or more of the rails 49 and 50, which ever may be desired, a round headed nail or screw 75, or bullet latch as it is sometimes called is secured so that it will cooperate with the terminating bend 76 of one of the spring members 67 to hold the panel in position, when the panel is moved to its uppermost limit. In the preferred form or in the illustrated embodiment, the sliding panel 55 is so arranged with respect to the opening 47, that the said opening is uncovered when the panel 55 has been moved to the lower position against a stop block 80, and the panel is provided with a control knob or button 81 by which it may be raised to close the opening 47, at which instance the panel 55 engages the stop blocks 82, and coincident therewith the free end 69 of the spring 67 passes over and springs behind the bullet catch 75 to hold the door in place, substantially as illustrated in Fig. 4. It is obvious of course, that in some instances it may be preferred to have the closure member 55 in the raised position when the instrument panel 48 is to be uncovered, in which instance it will be necessary to invert some of the parts, but it is intended that the purview of this invention shall cover such a structure. In the preferred form, however, it is desired that the opening 47 be uncovered when the panel 55 has been moved to its lower position, and that the same will be closed when the panel is raised to the latched position as illustrated in Fig. 4, whereupon the instrument panel 48 will be covered and the knob or button 81 of the panel 55 will be disposed substantially as indicated at 81'.

While the invention has been illustrated in detail in that form of cabinet appearing in Fig. 1, the same invention is adaptable to other forms of cabinet, such as illustrated in Figs. 6, 7 and 8, irrespective of whether the plan be that of 29a,

29b or 29c, or whether the sliding panel 55 be of the forms 55a, 55b or 55c. In either instance, the panel 55 may be formed in the shape desired, and then fitted into the guideways in the cabinet front piece, with the spring and latch device.

While the form of embodiment of the present invention as herein disclosed, constitutes a preferred form, it is to be understood that other forms might be adopted, all coming within the scope of the claims which follow.

What is claimed is as follows:

1. In a radio cabinet having a compartment to house a receiver, the combination comprising, a front wall for said cabinet providing a window-way, guide rails affixed to the cabinet wall in parallel arrangement on either side of said window-way, an instrument panel secured to said rails and being spaced from said front cabinet wall, a slidable closure running in said rails and adaptable to open and close said window-way, whereby access may be had to controls protruding through the instrument panel, or the same may be covered.

2. In a radio cabinet having a compartment and a front wall substantially closing the same, the combination comprising, a pair of guide rails secured to the cabinet wall, said front wall being apertured to provide a window-way therethrough between said guide rails, a closure member slideable within said guide rails operable to cover said window-way and to give access through the same, an instrument panel attached to said guide rails and being substantially spaced from said closure member to provide a recess, said instrument panel being apertured for the passage of instrument controls, and said recess being of sufficient depth to contain manipulating members secured to said controls.

3. In a radio cabinet having a front wall for substantially covering a receiving instrument contained therein, the combination comprising, guide rails mounted on said front wall and providing spacing members to the rear thereof, an apertured instrument panel secured to said rails so as to be spaced from said front wall, a closure member slideable within the said rails in position between the front wall and said instrument panel, said front wall being apertured throughout the major portion of the area between said rails and said aperture being of smaller dimension than said closure member.

4. In a radio cabinet having a front wall with a window-way of appreciable size therein for substantially covering the contents of said cabinet, the combination comprising, a closure for said window-way movable to completely close the same in one position and to expose substantially all of the same in the second position, guide rails secured to the front wall to keep said closure member, said rails providing spacers behind said closure, and an instrument panel secured to the rails and offset from said closure member by said spacers.

JOHN E. GRIMM.
